UNITED STATES PATENT OFFICE.

JOHN LENARD STUART, OF OAKLAND, CALIFORNIA, ASSIGNOR TO STUART MACHINE CO., OF SAN FRANCISCO, CALIFORNIA, A CORPORATION OF CALIFORNIA.

GROMMET MAKING AND SETTING MACHINE.

Application filed July 28, 1924. Serial No. 728,686.

To all whom it may concern:

Be it known that I, JOHN LENARD STUART, a citizen of the United States, residing at Oakland, in the county of Alameda and State of California, have invented certain new and useful Improvements in Grommet Making and Setting Machines, of which the following is a specification.

My invention relates to a machine for making grommets, eyelets, and the like, and setting the same in fabric or other material. The machine embodying my invention constitutes an improvement on the grommet making and setting machines disclosed in my United States Letters Patents Nos. 1,249,238 and 1,373,462, issued respectively December 4th, 1917 and April 5th, 1921.

On account of the features of novelty of the present invention, I am able to provide a machine which operates with greater accuracy and speed and more efficiently than those described in the said patents.

My invention is herein described and illustrated as embodied in a machine for making and setting grommets, for the reason that such is the principal use for which it is designed, but it will be apparent that the machine may be readily adapted for the making and setting of other similar objects, such, for example, as eyelets, without involving any material changes in the essential features of the invention, or departing in any degree from the spirit thereof. Moreover, changes, within the scope of the claims hereto appended, may be made in the form and construction of the machine, for reasons of mechanical or structural practicability, without in any way affecting the principles of the invention.

With this in view, a preferred embodiment of my present invention will now be fully described with reference to the accompanying drawings, wherein—

Fig. 1 is a vertical section of my grommet making and setting machine.

Figs. 2, 3 and 4 are sectional plan views taken approximately on the lines 2—2, 3—3 and 4—4 of Fig. 1 respectively.

Figs. 4^a and 4^b are, respectively, detailed vertical and plan views of the operating mechanism for the lower setting dies, Fig. 4^a being taken on the line 4^a—4^a of Fig. 4^b,

and Fig. 4^b being taken on the line 4^b—4^b of Fig. 1.

Fig. 5 is a partly broken sectional plan, 55 reduced in size, taken approximately on the line 5—5 of Fig. 1.

Fig. 6 is a vertical sectional view of the overrunning clutch mechanism indicated in Figs. 1 and 5.

Figs. 7, 8 and 9 are sectional views taken respectively in the direction of the arrows on the lines 7—7, 8—8 and 9—9 of Fig. 6.

Fig. 10 is a partly broken side elevation of the driving clutch mechanism indicated 65 in Fig. 1.

Fig. 11 is a plan view of the same taken on the line 11—11 of Fig. 10.

Fig. 12 is a plan view of the lower jaw member of the clutch.

Figs. 13 and 14 are sectional details taken on the line 13—14 of Fig. 11, showing the clutch dog in its two functional positions.

Fig. 15 is a detail vertical section of the clutch dog operating means, and is taken on 75 the line 15—15 of Fig. 16.

Fig. 16 is a sectional plan view of the same taken on the line 16—16 of Fig. 15.

Figs. 17 and 18 are diagrams representing, in end elevation, the clutch dog and 80 its operating means in two different positions.

Fig. 19 is a vertical section, enlarged, of the grommet forming die mechanism, and the grommet strip feed mechanism.

Fig. 20 is a vertical sectional detail of the grommet forming dies, showing their relative positions at the moment of forming the grommet.

Fig. 21 is a sectional plan view, enlarged, 90 of the grommet strip feed mechanism.

Fig. 22 is a vertical section of the same taken on the line 22—22 of Fig. 21.

Figs. 23 and 24 are sectional details of the grommet strip feed cam, taken on the 95 line 23—24 of Fig. 21, showing said cam in two different positions.

Fig. 25 is a perspective view, enlarged, of the grommet strip feed cam.

Fig. 26 is a perspective detail, enlarged, 100 of the rear end of the strip feed arm.

Fig. 27 is a vertical section of the washer-forming die mechanism and the washer-strip feed mechanism.

Fig. 28 is a sectional detail of the washer forming dies, showing their relative positions at the moment of forming the washer.

Fig. 29 is a transverse section of the washer strip guide, taken on the line 29—29 of Fig. 27.

Fig. 30 is a plan view of the washer-strip waste guide.

Fig. 31 is a transverse section of the end portion of the washer-strip waste guide, showing the waste cutting mechanism, and is taken on the line 31—31 of Fig. 32.

Fig. 32 is a longitudinal section of the same taken on the line 32—32 of Fig. 31.

Fig. 33 is a part sectional front elevation of the setting dies.

Fig. 34 is a vertical section of the same, taken on the line 34—34 of Fig. 33, and enlarged, showing the relative positions of the parts at the beginning of the setting operation.

Fig. 35 is a vertical sectional detail of the setting dies, showing their relative positions after having punched the hole in the material and before setting the grommet therein.

Fig. 36 is a similar view showing the relative positions of the setting dies at the conclusion of the setting operation.

Fig. 37 is a partly diagrammatic sectional view showing the relative positions of the upper setting die, the washer, material, and grommet immediately prior to the setting operation.

Fig. 38 is a sectional detail showing the completed grommet set in the material.

In the drawings, the reference numeral 1 designates a housing which encloses and acts as a supporting frame for the working parts of the machine. The upper portion of said housing is narrowed at one side, as shown at 2, in Figs. 2, 3 and 4, and in this narrowed housing portion there is formed a recess 3, Fig. 1, entering from the outside and forming a channel within which the material to be operated upon can be placed, without interfering with or becoming entangled in the enclosed operating parts of the machine.

In the lower portion of the housing 1 is positioned a suitable power device shown in Figs. 1 and 5 as an electric motor 4. Said motor has a shaft 5, provided with a worm 5', which drives a worm wheel 6, as indicated in Fig. 5. The worm wheel 6 is freely journaled upon a vertical shaft 7, and is connected therewith by means of an overrunning clutch indicated at 8, in Figs. 1 and 5, and illustrated in detail in Figs. 6 to 9 inclusive. The worm wheel 6 is provided with ratchet teeth 9 upon its upper surface, adapted to engage similar teeth 10 formed upon the lower surface of the member 11, said member being slidably secured by

means of a key 12 upon the shaft 7.

Springs 13, interposed between the member 11 and a flange 14 secured upon the shaft 7, normally hold the teeth 9 and 10 in engagement. This overrunning clutch enables the shaft 7 to be turned in one direction, by hand, when necessary, as for example, when adjusting or timing the various parts of the machine, without turning the motor 4 and worm gearing 5' and 6.

A fly-wheel 15, Fig. 1, is provided, and is geared to the shaft 7, as shown at 16. Said shaft, which revolves continuously, terminates in a clutch mechanism collectively designated by the numeral 17 in Fig. 1, and which serves to connect said shaft with an axially aligned upper shaft 18. The clutch mechanism 17 comprises a lower disk 19, Figs. 10 and 12, provided with one or more radially disposed grooves 20, there being four such grooves shown in the drawings. Said disk 19 is secured to the shaft 7, as by means of a key 21. An upper disk member 22, Figs. 10 and 11, is secured, as by means of a key 23, to the upper shaft 18, and is positioned with its lower face adjacent to the upper face of the lower disk member 19. Said upper disk 22 is provided with a diametrically disposed dog 24, pivotally mounted at 25 for vertical swinging movement into and out of any one of the grooves 20 of the lower disk 19, as shown respectively in Figs. 14 and 13. A spring 26, Fig. 10, serves to press the dog 24 into one of its coacting grooves 20, and when such engagement takes place, the two disks 19 and 22 are compelled to rotate together, thus transmitting power to the upper shaft 18.

The clutch is operated by a latch mechanism collectively designated by the numeral 27 in Fig. 1 and controlled by a cord 28 and foot operated treadle 29 in the base of the machine, an opening 30 being provided in the front of the housing 1 to allow access to said treadle. The cord 28 is connected at its upper end with a horizontally sliding latch member 31, Figs. 15 and 16, and this latch member is provided with an upwardly extending lip 32 adapted to engage the end of a bolt 33 slidably mounted immediately above said latch member. The latch member 31 has also a vertical swinging movement to enable its lip 32 to free the end of the bolt 33. Under normal conditions, the latch member 31 is retained in the position shown in Figs. 15 and 16 by springs 34 and 35, and the bolt 33 is retained in the position shown by a spring 36. In this position the projecting beveled end 37 of the clutch dog 24 rests upon the bolt 33, as indicated in Fig. 17, and said dog is thereby prevented from dropping into one of the grooves 20 of the lower clutch member 19. However, when the latch member 31 is moved toward the right, as viewed in Fig. 15, by means of

the cord 28 and treadle 29, the bolt 33 is withdrawn from beneath the clutch dog 24 and said dog thereupon drops into one of the grooves 20, and causes the two clutch members to rotate together.

The latch member 31 is provided with an inclined face 38, which is immediately engaged by the end 37 of the released clutch dog 24, and by such engagement said latch member is depressed, as indicated in Fig. 18, to cause the lip 32 to free the end of the bolt 33, thereby allowing said bolt to return to its normal outward position, to be ready to raise the clutch dog 24 out of the groove 20 upon its next revolution. The upper portion of the clutch and the upper shaft 18 can, therefore, only make one complete revolution without coming to rest, this one revolution being sufficient to complete one cycle 20 of operations of the machine. Even if the treadle 29 be held down, the ratchet member 31 will still be depressed, as indicated in Fig. 18, by the end 37 of the clutch dog 24, thereby allowing the bolt 33 to return to its 25 normal position ready to raise said dog and release the clutch upon the completion of one revolution thereof.

The upper vertical shaft 18, Figs. 1 and 4 of the drawings, drives, by means of worm gearing indicated at 39, a horizontal shaft 40, upon which is fixed a cam 41, Figs. 1, 4^a and 4^b. Said cam operates a bifurcated lever 42, fulcrumed at 43, and the rear end of said lever imparts reciprocating motion to the grommet forming die shank 44, Fig. 1, which is slidably mounted in a fixed guide 45. Said die shank 44 has secured to its upper end a grommet forming die 46, Fig. 19, and a slideable sleeve 47 surrounds said die. Said sleeve has a limited vertical movement upon the shank 44 and the die 46, and is normally held at the upper limit of its movement by springs 48. A central bore 49 is formed through the die 46 and the shank 44.

The grommets are initially and partially formed from a web or strip of suitable material, such, for example, as sheet brass. Said strip, numbered 50, may be carried in any desired manner, as, for example, upon a spool 51, Fig. 1, suitably mounted at the rear of the housing 1, and is fed horizontally and forwardly above the die 46, and between it and a co-operating stationary upper die 52, Fig. 19. Said upper die is secured as shown in a horizontal plate member 53 of the housing 1, and is provided with a vertically movable clamping sleeve 54, and a stationary central punch 55, the latter being secured to the die 52 by any suitable means, as, for example, a pin 56 extending through a cap or plug 57 screwed in the upper end of the die 52. A spring 58 normally retains the slideable clamping sleeve 54 in its lowermost position, as shown.

When the lower die shank 44 is raised by the action of the lever 42 and the cam 41, the die 46 first draws out the central tubular portion of the grommet, and by co-operation with the fixed upper die 52, forms said grommet, but does not cut it out from the strip 50. During this drawing operation, the central portion of the grommet is clamped between the upper end of the lower die 46 and the lower end of the upper movable sleeve 54, and at or near the conclusion of said drawing operation, the central hole in the grommet is punched by the upper fixed punch 55 entering the bore 49 in the die 46, as shown in Fig. 20. The lower die then retreats downwardly and the grommet strip 50 is advanced to a new position ready for the partial formation of a new grommet.

The strip 50 is advanced by means of a swinging arm 59, Figs. 19, 21 and 22, which carries a depending pin 60 adapted to enter and engage the upwardly drawn central portions 50' of the partially formed grommets. Said lever 59 is mounted for vertical swinging movement at 61, Figs. 21 and 22, in a carrier 62, which is itself mounted for horizontal swinging movement upon a fulcrum 63. The lever 59 has formed upon it a lug 64, Figs. 21, 22, 23, 24 and 26, adapted to be engaged both by a face cam 65 and by a radial cam 66, both said cams being formed upon a collar 67, Figs. 21, 23, 24 and 25, secured to the vertical shaft 18 by a key 67', Fig. 4. The rotation of said shaft, therefore, first lifts the lever 59 from the position shown in full lines in Figs. 19 and 22, to free its pin 60 from the grommet portion 50', then moves said lever rearwardly to the position shown in dotted lines in Fig. 21, then allows said lever to drop to cause its pin 60 to engage the next succeeding grommet portion 50', as indicated in Fig. 19, and finally allows said lever to be drawn forwardly to its initial position by a spring 68, Fig. 21, thereby advancing the grommet strip 50 the required distance. A stop 68' is provided to limit the forward movement of said arm 59.

The vertical shaft 18 also drives, through the worm gearing 69, Figs. 1 and 2, a horizontal shaft 70 mounted in the upper portion of the machine and carrying a cam 71, which operates a forked lever 72. Said lever is fulcrumed at 73, and its rear end operates a washer forming die shank 74, mounted for vertical reciprocating movement in a guide 75, Fig. 1. The die shank 74 has secured thereto, in any suitable manner, not shown, a sleeve 76. A die 77 is mounted for limited vertical movement within the end portion of said sleeve, and is normally held in its lowermost position, as shown, by springs 78. A central punch 79, extending through the die 77, is secured to the shank 130

74 by any desired means, as, for example, by a pin 80. The washer forming die 77 cooperates with a lower stationary die 81 secured as shown in a horizontal portion 82 of the housing 1.

When the die shank 74 is moved downwardly, by the action of the cam 71, the die 77 cooperates with the fixed die 81 to partially form a washer in a blank or strip 83 of suitable material, as, for example, sheet brass, and at or near the completion of the forming process, the die 77 remaining stationary and the shank 74 and the central punch 79 continuing their downward movement, said punch is forced through the strip 83 and into a bore 84 formed in the lower fixed die 81, thus punching the central hole 88' in the washer, as shown in Fig. 28. The washer, however, is not punched out of the strip 83. The strip 83 may be carried in any desired manner, as for example, upon a spool 85, Fig. 1, mounted upon the back of the housing 1, and is fed forwardly above the horizontal housing plate 82 and between the dies 77 and 81.

The feeding of the washer strip 83 is accomplished in a manner similar to that of the grommet strip 50 described above. An arm 86, Fig. 3, is mounted upon a pin 87 for vertical swinging movement in a carrier 88, which in turn is mounted upon a pin 89 for horizontal swinging movement. The lever 86 is provided with a lug 90 adapted to be engaged both by a face cam 91 and by a radial cam 92, both said cams being formed upon a collar 93 secured to the shaft 18 by a key 93'. The rotation of said shaft 18 therefore causes the arm 86 to be initially lifted to free its pin 94, Fig. 27, from the washer strip 83 and then to be moved rearwardly and allowed to drop to cause said pin to engage the next succeeding hole 88' in said strip, and finally to be moved by a spring 95, Fig. 3, forwardly to advance the strip the required distance. A pin 96, Fig. 27, depending from the upper die sleeve 76, is adapted to be moved down into the previously formed hole 88' in the strip 83 to act as a stop in limiting the advance movement of said strip.

The washer strip 83 with the partially formed washers therein is fed through a guide 97, Figs. 1, 3 and 29, said guide having upturned edges, as shown, to overlie the edges of the strip 83. A similar guide 98, Fig. 1, is provided for the grommet strip 50. The guides 97 and 98 carry their respective washer and grommet strips to the forward portion of the machine, where they are aligned between the upper and lower setting dies to be presently described.

The cam 71 mounted upon the upper horizontal shaft 70, Figs. 1 and 2, also operates a forked lever 99, fulcrumed at 100, whose forward end imparts reciprocating vertical

motion to an upper setting die mechanism slidably carried in a guide 101. Said die mechanism comprises a central shank 102, Fig. 33, which is positively moved by the lever 99, and an outer member 103 which has a limited vertical movement upon said shank, and which is normally held at the lower limit of its movement by springs 104. The lower end of the shank 102, as shown in Fig. 34, is provided with a central punch 105, and a curling or setting die face 106 surrounding said punch. The lower end of the sleeve 103, which normally extends below the die face 106 of the shank 102, is provided with a complementary curling face 107, and also with a cutting edge 107' adapted to coact with a stationary tubular member 108 secured in the fixed housing plate 82, to cut out the washer from its strip 83. The fixed tubular member 108 extends through said plate 82 and carries upon its lower end a slideable clamping member 109. Rods 110, Fig. 33, secured to said clamping member 109, extend upwardly therefrom and are secured to a collar 111 which is connected by cushioning springs 111' with the sleeve 103. A spring 112, Figs. 1 and 34, assists in retaining the clamping member 109 in its uppermost position.

The cam 41, secured upon the lower horizontal shaft 40, operates a double forked lever 113, Figs. 1, 4^a and 4^b, fulcrumed at 114, whose forward end operates the outer portion of the lower setting die mechanism. Said cam 41 also operates a single forked lever 115, fulcrumed about the pin 114 with its rear forked end lying between the double end of the lever 113, as shown in Fig. 4^b. A depression 116 is formed in the cam 41, to permit said lever 115 to have some movement independently of the lever 113. The forward end of the lever 115 operates the inner portion of the lower setting die mechanism. The lever 113 is connected, as shown, with a sleeve 117, Figs. 1 and 33, mounted for vertical sliding movement in a guide 118. The upper end of said sleeve is formed with a curling or setting face 119, as shown in Figs. 35 and 36, to coact with the faces 106 and 107 of the upper die members. The lever 115, Figs. 1 and 33, is connected as shown with a tubular punching member 120 slidably mounted in the sleeve 117. The upper end of said tubular member 120 is formed as shown in Figs. 35 and 36, at 121, to pass through the tubular portion of the grommet and to cooperate with the upper punch 105 to punch the hole in the material 122 in which the grommet is to be set.

The tubular punching member 120 is rotated at a rapid rate by means of a pulley 123 secured thereupon, Figs. 1 and 33, and a belt 124 connecting said pulley with a pulley 125 on the motor shaft 5. A journal 13

126, Fig. 1, is preferably provided for the lower end of the rotating tubular punch member 120.

In the operation of the machine, the material in which the grommet is to be set is placed between the housing plates 82 and 53, and rests upon a fixed clamping block 127 secured to the plate 53, as shown in Fig. 34. The treadle 29 is then depressed 5 causing the clutch 17 to connect the power shaft 7 with the upper operating shaft 18, thereby rotating the latter through one complete revolution. This revolution of the shaft 18, in addition to partially forming 10 a grommet and a washer in the respective strips 50 and 83, as previously described, causes the setting dies to move in the following manner:

The upper die members 102 and 103, Fig. 20 34, move downwardly, the outer sleeve member 103 punching out a washer 128 from its strip 83 and forcing it down through the tubular guide member 108 on to the top of the material 122. The clamping member 25 109 is also moved downwardly by its rods 110 to clamp the material 122 between its lower face and the fixed block 127. At the same time, the lower die members 117 and 120 are moved upwardly, the outer edge 30 119' of the sleeve 117 cooperating with an aperture 53' in the plate to punch out the grommet 129 from its strip 50 and carrying said grommet up against the lower surface of the material 122. The inner and rotating 35 125 lower punch 120, moving upwardly and cooperating with the downwardly moving upper punch 105, forms the hole in the material 122, as shown in Fig. 35, the spinning or rotating of said lower punch member insuring a clean cut hole. The continued upward movement of the lower die members 117 and 120 forces the tubular portion 50' of the grommet 129 through the hole in the material 122 and through the aligned hole 40 45 50' 53' in the washer positioned thereabove. The depression 116, Fig. 4^a, then permits the lower rotating punch 120 to drop slightly, while the grommet 129 is forced still further up by the continued upward movement of the lower die sleeve 117, the tubular portion of the grommet being initially expanded by the face 106 of the upper central die shank 102. The upper face 119 of the lower die sleeve 117 now meets the lower face 107 of the upper die sleeve 103, the outer or peripheral portions of the grommet 129 and the washer 128 being clamped therebetween, and the material 122 being clamped between said grommet and washer. 55 60 65 The lower die sleeve 117 now comes to rest and the continued downward motion of the upper die shank 102, moving down within the upper die sleeve 103 against the compression of the springs 104, curls or clinches the initially expanded tubular portion of

the grommet 129 over the washer 128, as illustrated in Fig. 36. The dies then separate and return to their initial positions, and the strips 50 and 83 are advanced by the mechanism above described to present 70 the next partially formed grommet and washer in alignment with the setting dies, and to present new portions of said strips to the grommet and washer forming dies. When the dies begin to separate, the upper 75 80 die sleeve 103 is returned by the springs 104 to its lowermost position upon the shank 102, thereby stripping the set grommet from the face 106 of said shank.

The waste portion of the washer strip 83, after the washers have been stamped therefrom, is disposed of in a suitable manner to keep it out of the way of the material being operated upon. For this purpose, I provide a guide channel 130, 85 Figs. 1 and 30, leading up the front of the housing 1, thence into said housing at its top, and rearwardly therethrough to its rear, through which the waste portion of the strip 83 passes. At the extreme rear 90 95 of this channel, I provide means for cutting the waste strip portion into lengths which will enable its ready disposal. The waste strip 83 passes through a block 131, Figs. 1, 31 and 32, and in this block operates a sliding knife 132, which is secured by a connection 133 to the upper end of the washer forming die shank 74. Thus at each upward movement of said die shank, a length of the waste strip 83 is cut off and 100 allowed to drop outside the housing 1 to any suitable place of disposal, not shown.

The waste portion of the grommet strip 50 is also cut into lengths by a knife indicated at 134, Fig. 1, connected with the lower setting die sleeve 117, and operating in a block 135 to cut the strip 50 into lengths, such lengths dropping outside the housing 1 to any convenient place of deposit. The waste from the washer and grommet forming dies is also carried from within the machine by chutes 136 and 137 respectively, and the waste punchings from the material are likewise disposed of by dropping through the tubular lower punch 120, and being carried from within the machine by a chute 138.

Each complete cycle of operations, which results from one revolution of the vertical shaft 18, therefore involves the following 110 115 120 125 130 automatic movements:

(1) A grommet and a washer are partially formed, by the grommet and washer forming dies, in the respective blank strips 50 and 83, the central holes being punched in both, but said grommet and washer are not cut out from their strips.

(2) The material or work in which the grommet is to be set is clamped between the members 109 and 127, the grommet receiv-

ing hole is punched in said work and a previously formed and positioned grommet and washer are stamped out of their respective strips and set in said hole, after which the 5 work is released by said clamping members.

(3) The grommet and washer strips 50 and 83 are advanced, to present fresh surfaces to the forming dies and to present the 10 next partially formed grommet and washer in alignment with the setting dies, and the waste end portions of said strips, from which the grommet and washer have been stamped, are cut off. The drive shaft 18 then automatically comes to rest until the 15 clutch 17 is again operated, by the treadle 29, to start a new cycle of operations.

I claim:—

1. In a machine for making and setting grommet members with co-operating washer 20 members, means for supporting a blank having one of said members partially formed therein; means for automatically positioning the other member in setting relation thereto; and means for removing the 25 partially formed member from its blank and setting it with said other member in the work.

2. In a machine for making and setting grommet members with cooperating washer 30 members; means for supporting a strip blank having one of said members partially formed therein; means for removing the partially formed member from its strip; means for advancing said strip to carry the 35 partially formed member from the partial forming means to the removing means; means for automatically positioning the other of said members in setting relation to the removed member; and means for setting 40 said members in the work.

3. In a machine for making and setting grommet members with cooperating washer members; means for partially forming one 45 of said members in a blank; means for automatically positioning the other member in setting relation thereto; and means for removing the partially formed member from its blank and setting it with said other member in the work.

4. In a machine for making and setting grommet members with cooperating washer members, means for partially forming one 50 of said members in a strip blank; means for removing the partially formed member from its blank; means for automatically positioning the other of said members in setting relation to the removed member; means for setting said members in the work; and means for advancing said strip to carry the 55 first mentioned member from the partial forming means to the removing means.

5. In a machine for making and setting grommet members with cooperating washer members, means for supporting and advancing 60 a strip blank having a succession of one

of said members partially formed therein; means for successively and automatically positioning the other of said members in setting relation thereto; and means for successively removing the partially formed 70 members from their strip and setting them with said other members in the work.

6. In a machine for making and setting grommet members with cooperating washer members, means for successively partially 75 forming one of said members in a strip blank; means for successively and automatically positioning the other of said members in setting relation thereto; means for successively removing the partially 80 formed members from said strip and setting them with said other members in the work; and means for advancing said strip to carry the first mentioned members from the partial forming means to the removing 85 and setting means.

7. In a machine for making and setting grommet members with cooperating washer members; means for supporting a blank having one of said members partially 90 formed therein; means for forming the other of said members; and means for removing the partially formed member from its blank and setting it with said other member in the work. 95

8. In a machine for making and setting grommet members with cooperating washer members, means for partially forming one 100 of said members in a blank; means for forming the other of said members; and means for removing the partially formed member from its blank and setting it with said other member in the work.

9. In a machine for the described purpose, means for supporting a strip blank 105 having a succession of grommets partially formed therein; means for successively removing the grommets from said strip and setting them in the work; and a member adapted for swinging movement in two different planes to successively engage the partially formed grommets for advancing said strip. 110

10. In a machine for the described purpose, means for partially forming a grommet in a blank strip comprising a lower reciprocating drawing die, an upper fixed die aligned and cooperating with the lower die, a punch carried by said upper die for forming the central hole in the grommet, and a retractable clamping sleeve surrounding said punch for clamping the central portion of the grommet against the lower die during said punching operation; means for removing the partially formed grommet from the strip and setting the same; and means for advancing the strip to carry the grommet from the forming means to the setting means. 120

11. A machine for the described purpose 125

- comprising means for partially forming a grommet in a blank strip; means for partially forming a washer in a second blank strip; means for removing said grommet and said washer from their respective strips and setting the same in the work; and means for advancing said strips to carry the grommet and the washer from the forming means to the setting means.
12. A machine for the described purpose comprising means for partially forming a grommet in a blank strip; means for partially forming a washer in a second blank strip; means for removing said grommet and said washer from their respective strips and setting the same in the work; and means for advancing said strips in timed relation to carry the partially formed grommet and washer into alignment with the setting means.
13. A machine for the described purpose comprising means for partially forming a grommet in a blank strip; means for partially forming a washer in a second blank strip; means acting simultaneously with said forming means for removing a previously partially formed grommet and washer from their respective strips and setting the same in the work; and means for advancing said strips to carry the partially formed grommet and washer into alignment with the setting means.
14. A machine for the described purpose comprising means for partially forming grommets successively in a blank strip; means for partially forming washers successively in a second blank strip; means for successively removing the partially formed grommets and washers from their respective strips and setting the same in the work; and means for advancing said strips to carry the grommets and washers from the forming means to the setting means.
15. In a machine for the described purpose, means for supporting a blank having a partially formed grommet therein; means for supporting a second blank having a partially formed washer therein; and means for removing the grommet and washer from their respective blanks and setting the same in the work.
16. In a machine for the described purpose, means for supporting and advancing a strip blank having a succession of grommets partially formed therein; means for supporting and advancing a second strip blank having a succession of washers partially formed therein; and means for successively removing said grommets and washers from their respective strips and setting them in the work.
17. In a machine for the described purpose, means for holding a strip blank having a grommet partially formed therein; a means for holding a second strip blank hav-
- ing a washer partially formed therein; means for advancing said strip blanks to position the partially formed grommet and washer in alignment; and means for removing the grommet and washer from their respective strip blanks and setting the same in the work.
18. In a machine for the described purpose, means for holding a strip blank having a succession of grommets partially formed therein; means for holding a second strip blank having a succession of washers partially formed therein; means for successively removing the partially formed grommets and washers from their respective strip blanks and setting the same in the work; and means for advancing said strips in timed relation to the movements of the setting means.
19. In a machine for the described purpose, means for holding strip blanks having grommets and washers respectively partially formed therein; means for removing the partially formed grommets and washers from their respective strips and setting the same in the work; and reciprocating members adapted to advance said strips by successive engagements therewith to carry the partially formed grommets and washers into alignment with the setting means.
20. In a machine for the described purpose, means for holding a strip blank having a grommet partially formed therein; means for automatically positioning a washer in alignment with the partially formed grommet; means operating through the partially formed grommet and said washer to punch the grommet receiving hole in the work; and means for removing the grommet from its strip and setting it with said washer in said hole.
21. In a machine for the described purpose, means for holding strip blanks having grommets and washers respectively partially formed therein; means operating through the partially formed grommets and washers for punching the grommet-receiving hole in the work; and means for removing the grommet and washer from their respective blanks and setting the same in said hole.
22. In a machine for the described purpose, means for holding a strip blank having a partially formed grommet therein; a rotating punch member adapted to form the grommet-receiving hole in the work; and means cooperating with said punch member for removing the partially formed grommet from the strip and setting the same in said hole.
23. In a machine for the described purpose, means for holding a strip blank having a grommet partially formed therein; a rotating punch member operating through said grommet to form the grommet-receiving hole.

ing hole in the work; and means cooperating with said punch member for removing the partially formed grommet from its strip and for setting the same in said hole.

5 24. A machine for the described purpose, comprising means for forming a grommet; a rotating punch member adapted to form the grommet-receiving hole in the work; means for carrying the grommet from the 10 forming means into alignment with said punch member; and means cooperating with said punch member for setting the grommet in said hole.

15 25. A machine for the described purpose, comprising means for forming a grommet; and associated die mechanism for setting the same comprising a rotating punch member adapted to operate through the grommet in punching the grommet-receiving 20 hole in the work, and means cooperating with said punch member to set the grommet in said hole.

25 26. A machine for the described purpose, comprising means for forming a grommet; and an associated die mechanism for setting the same comprising a reciprocating and rotating punch member operating through the grommet to punch the grommet-receiving hole in the work, and reciprocating 30 means cooperating with said punch member to set the grommet in said hole.

35 27. In a machine for the described purpose, means for holding a strip blank having a partially formed grommet therein; reciprocating means adapted to remove the partially formed grommet from said strip; a rotating punch member within said removing means for forming the grommet-receiving hole in the work; and an aligned 40 reciprocating member adapted to cooperate with said removing means and said punch member to set the grommet within said hole.

45 28. In a machine for the described purpose, means for holding a strip blank having a grommet partially formed therein; means for holding a second strip having a

washer partially formed therein; means for aligning the partially formed grommet and washer; reciprocating means for removing the washer from its strip; a rotating punch member operating through said grommet to form the grommet-receiving hole in the work; and a reciprocating member for removing the washer from its strip, said member cooperating with the grommet-removing means and the punch member to set the grommet and washer in said hole.

50 29. In a machine for the described purpose, means for holding strip blanks having a grommet and a washer respectively partially formed therein; means for removing the partially formed grommet and washer from their respective strip blanks and setting them in the work; and means for clamping the work in position during the setting 55 operation.

55 30. In a machine for the described purpose, means for clamping the work; means for positioning blanks having a washer and a grommet respectively partially formed 60 therein in alignment with said clamping means; and means for removing the washer and grommet from their respective blanks, carrying them through said clamping means, and setting them in the work.

75 31. A machine for the described purpose comprising means for forming a grommet and a cooperating washer therefor; means for setting the same in the work; means for clamping the work in position 70 during the setting operation; and means for transferring the grommet and washer from the forming means to the setting means.

35 32. A machine for the described purpose, comprising means for forming a grommet and a cooperating washer therefor; means for clamping the work; and means operating through said clamping means to set the grommet and washer in the work.

80 40 In testimony whereof I have signed my name to this specification.

JOHN LENARD STUART.
